Primary Examiner — Cynthia Underwood

(74) Attorney, Agent, or Firm — Ladas & Parry, LLP

(57) **CLAIM**

The ornamental design for a clip, as shown and described.

DESCRIPTION

FIG. 1 is a perspective view viewed from top side of a clip showing our new design;

FIG. 2 is a perspective view viewed from bottom side thereof;

FIG. 3 is a front elevation view thereof;

FIG. 4 is a right side elevation view thereof;

FIG. 5 is a top plan view thereof;

FIG. 6 is a bottom plan view thereof;

FIG. 7 is a sectional view taken along line 7-7 in FIG. 3

FIG. 8 is a sectional view taken along line 8-8 in FIG. 4; and, FIG. 9 is a top perspective view shown with the clip in an environment of use, the broken lines forming no part of the claim.

1 Claim, 6 Drawing Sheets
